UNITED STATES PATENT OFFICE.

HARVEY C. HALL, OF BROOKLYN, NEW YORK.

PUMP.

SPECIFICATION forming part of Letters Patent No. 274,760, dated March 27, 1883.

Application filed November 10, 1882. (No model.)

To all whom it may concern:

Be it known that I, HARVEY C. HALL, of the city of Brooklyn, in the county of Kings and State of New York, have invented a certain new and useful Improvement in Pumps, of which the following is a specification.

My invention relates to hand and power lift-pumps, and also to air or vacuum pumps; and the objects of the invention are to provide a pump which may be manufactured at a less cost than those heretofore made, which is more simple in its construction, and which may be easily and quickly taken apart in case it is desired to renew any of its parts or in case it becomes clogged.

To this end my invention consists in various novel details of construction and combinations of parts hereinafter described, and set forth in the claims, whereby the desired result is attained.

In the accompanying drawings, Figure 1 represents a central vertical section of a pump embodying my invention. Fig. 2 represents a sectional view of a loose flange or discharge-valve of modified form. Fig. 3 represents a plan of said flange or valve. Figs. 4, 5, and 6 represent detail sectional views of a portion of the pump-chamber and modified forms of loose flanges or discharge-valves. Fig. 7 represents a central vertical section of a pump, also embodying my invention, but in which the pump-chamber is provided with an integral flange containing a discharge-valve. Fig. 8 represents a plan view of the pump shown in Fig. 7; and Fig. 9 represents a central vertical section of a pump embodying my invention and adapted to be used as an air-pump, a portion of the discharge-valve being broken away.

Similar letters of reference designate corresponding parts in all the figures.

Referring first to Fig. 1, A designates the pump-chamber, which consists simply of a casting open at the top and capable of being made without the necessity of using a dry-sand core. The suction-pipe B communicates with the chamber at the bottom, and the chamber is provided with a suction-valve, C, here shown as having a face, a, of rubber, leather, or other material. This valve may be of any other suitable construction. The upper part of the chamber

A is of larger diameter than the lower part, and is provided with an annular groove, b, wherein is secured a packing, c, of leather, hemp, rubber, or other material, which forms a valve-seat. At a considerable distance above the valve-seat c the chamber is provided with a discharge-spout, A', and at the top it is provided with open bearings d.

D designates a ring, which may be of cast metal, and rests on the valve-seat c. This ring or flange is provided on the inner side with a groove, e, wherein is secured a packing, f, of any suitable material.

E designates the plunger, which fits within the ring or flange D and packing f. The ring D serves both to close the chamber and to form a discharge-valve, and it is guided in its rising and falling movements by ribs g, formed on the interior of the upper part of the chamber, or, if desirable, on the outer edge of the valve D. The plunger E is operated by a hand-lever, F, which is connected therewith by a link, F'. This link is secured to the plunger by a pin, h, which may be made of brass, and is inserted directly through the plunger and the eye of the link. The end of the lever might be connected directly with the plunger, if desired, and the link dispensed with. The lever F is shown as provided with integral journals or pivots i, which rest in the bearings d, and are secured therein by pins i'. The plunger E may be made of metal, glass, or any other suitable material. If practicable, however, I prefer to make it of hard wood, because of its cheapness, and because it may be so cheaply renewed when worn out, and also because it will not rust, and will work easily and without cutting on the packing f. The top of the plunger is slightly concave, as at j, so that in its upward stroke it will always take up water, which will remain therein while the pump is at rest, and prevent the plunger from drying out.

The water contained in the cavity into which the link F' extends will not become stagnant or foul, because the plunger in its downward stroke is entirely immersed in the water, and the flow of the water over it and the side movement of the link will cause the water in said cavity to be all the time changing. When the plunger is pushed down the discharge-valve D is lifted and water flows upward under and

past it, and one great advantage of this form of valve is that as the water can discharge around its entire periphery the valve will be lifted but little, and yet so large an opening 5 will be afforded that the water will not be discharged with any considerable velocity, and therefore will not be liable to wash over the top of the chamber. When the plunger is raised a suction will be created in the chamber, and the valve D will be held tightly to its seat while the plunger ascends. If the packing f be new, and there be any considerable friction between it and the plunger, the latter would or might have a tendency to lift the 10 valve in its upward movement, and thus prevent the formation of a vacuum. This I prevent by a novel formation of the plunger, which has a slight taper at k, and the portion above the taper made slightly smaller in diameter 15 than the portion below. In the downward movement of the plunger the taper k passes below the packing f, and the portion of reduced diameter fits loosely in the packing. Consequently when the plunger commences its 20 upward movement, although it creates a vacuum, it does not have any tendency to lift the valve D, and therefore said valve will be "caught" by the vacuum and held tightly to its seat by atmospheric pressure before the 25 larger part of the plunger comes in contact with the packing f. This reduction of the upper part of the plunger has other advantages. When the plunger is descending the valve D is lifted and held up by the water-pressure, 30 and there might possibly be a tendency to cant the valve out of a horizontal position. When the portion of the plunger of reduced diameter passes the packing f the valve is freed from the plunger, and can at once resume 35 its horizontal position and drop squarely on the seat c. As soon as the taper on the plunger passes the packing f an additional opening is afforded between the plunger and the packing, and as a new outlet is thus afforded for 40 the water the valve will fall somewhat, and will seat itself gradually as the extent of opening between the plunger and the packing f increases. With the slight taper here shown this advantage would scarcely be apparent; 45 but in large pumps, where the annular valve D is of large diameter and heavy, the plunger may have a much greater taper, and would then cause the valve to seat itself very gradually and without much shock. I am aware 50 that even where there is a slight taper of the plunger, as here shown, there would be very small loss by reason of leakage downward around the plunger during a small part of its upward stroke; but the advantages attained 55 will more than compensate for any such loss. One great advantage of this pump is the ease with which it may be taken apart in case it clogs, or if it is desired to renew any of its parts. All that is necessary is to knock out 60 the pins i, and then the handle F, and with it the plunger E, may be taken out, the valve D

may be lifted off, and the suction-valve C may be taken out, thereby dismantling the whole pump without unscrewing a bolt or a nut. As bolts and nuts used in pumps soon become 70 rusted, this is of immense advantage. The discharge-valve is readily accessible from the open top of the pump at all times, and may be raised to take out any obstructions, or examined, without any trouble whatever. 75

In Figs. 2 and 3 I have shown a discharge-valve, D, of different construction. The valve is tapered on its inner side, and contains an expanding and contracting packing-ring, f', made of Babbitt metal or other material, and held in place by a ring or plate, D', secured to the valve D by screws l, or otherwise. This ring is made in three or more sections, and the sections adapt themselves readily to the plunger, even though it be worn, and form a comparatively tight joint between the plunger and the valve D. 85

In Fig. 4 the pump-chamber A has a metallic seat, c', instead of a flexible seat, c, as in Fig. 1, and the valve D may be made of Babbitt metal or other soft metal to loosely fit the plunger E. The valve is provided with a leather or other soft packing, f, secured in a rabbet by a ring, D², screwed into the valve D. The ring D² may also be of Babbitt or 95 analogous metal, and it and the valve D may be cast of such metal in iron molds, with their screw-threads complete.

In Fig. 5 the space between the plunger E and chamber A is closed by a valve, D, consisting of a ring having a packing, f, secured upon its face by a ring, m. The packing f fits the plunger and bears on the raised valve-seat c'. 100

In Fig. 6 the space between the chamber A and pump-plunger E is closed by a ring or valve, D, which rests on a seat, c', and is rounded in a vertical direction on its inner side, so as to fit the plunger snugly and still allow the latter to vibrate slightly, as it would do if operated by the lever F without any guide. This form of valve is well adapted for large pumps, in which the plungers are operated by long rods, and there is little side movement and wear of the plunger. This valve 105 may be made of Babbitt metal or analogous metal, and will have but little friction and wear on the wood plunger. Of course there would be a slight leakage between the valve D and plunger; but as the water always 110 stands above the valve it could not leak air, and the pump could be made of a capacity slightly larger than would be otherwise necessary. The loss by leakage would be more than compensated for by the extreme simplicity and the absence of packing. 115

The parts shown in Figs. 7 and 8 which correspond with the parts previously described I have designated by the same letters of reference. In this pump the chamber A is provided with an inwardly-projecting flange, A², 120 through which the plunger E works, and which

contains discharge-openings *n*. This flange may be made integral with the chamber; or it may be made separate therefrom for convenience in casting, and secured therein in any suitable way. The discharge - openings are closed by an annular valve, *D*, which is faced with a packing, *f*, that also fits the plunger. The valve *D* is provided with spurs or projections *o*, which pass through the packing *f*, and prevent the latter from "crawling" out from under the valve. The flange *A*² may be bushed with a ring, *p*, of brass or other material which will not rust and will wear well on the wood plunger. This ring may be rolled down onto the iron, and is rounded in a vertical direction, so as not to gall or cut the plunger. The top of the plunger is depressed or concave, as shown in dotted lines, for the purpose before described. The operating-lever *F* is fulcrumed by a pin, *q*, in a fulcrum-piece, *G*, which is provided with an arc-shaped groove, *r*, fitting the top of the chamber, and said piece is adapted to be adjusted thereon horizontally, so that the lever or handle *F* will stand in any desired position relatively to the discharge-spout *A*¹. The fulcrum-piece *G* is secured in place by a set-screw, *s*, or otherwise. This pump may be taken apart with the same facility as the pump shown in Fig. 1 by simply taking out the pin *q*. Of course the plunger may be tapered, like that shown in Fig. 1. If valves of lead were substituted for those used in the pump shown in Fig. 1, the pump would be very desirable for pumping acids, and either of the pumps may be used, and is well adapted for household purposes, for ship-pumps, for farm-pumps, for pumping out foundations or doing other work where the water is dirty or gritty, and for raising water in small or large quantities for manufacturing purposes. Where the plungers are of large size I prefer to make them of wood, and if several pieces are used they may be secured by a ferrule or band or a cap at each end of the plunger. Either of the pumps before described might be used as an air-pump by dispensing with the discharge-spout and retaining in the top or enlarged upper part of the pump-chamber the liquid, which will be displaced by the first downward stroke of the plunger; but in Fig. 9 I have represented a pump which is particularly intended for an air-pump, although it also might be used as a pump for liquid. In said Fig. 9, *A* designates the pump-chamber, which is provided with an inwardly-extending flange, *A*², in which are discharge-openings *n*, covered by a valve, *D*, of leather or other suitable material. The inlet-pipe *B* is here placed in the upper part of the chamber, and is provided with the inlet-valve *C*. *E* designates the plunger, which may be of wood or metal, and which is operated by a link or rod, *F*. The operation of this pump is very simple. On starting the pump I lift the discharge-valve *D* slightly and pour in oil, water, or other liquid until the chamber is entirely filled up to

and above the flange *A*², the plunger being at the time raised. When the plunger is forced down there is a large displacement of liquid, which passes through the valve-openings *n*, 70 and is retained over the valve *D* in the upper part of the chamber and around the plunger. The plunger is now raised and air is drawn in through the valve *C*, while a small quantity of liquid is drawn down as leakage around the 75 plunger, the plunger being purposely and preferably left without packing. The plunger is now forced down, and at first simply decreases the volume of air in the pump-chamber; but as soon as the plunger passes into the liquid 80 in the chamber the liquid is raised in an annular column around the plunger and carries or forces every cubic inch of air out through the valve-openings *n*. The discharge at every downstroke of the small quantity of liquid 85 which leaks in at every upstroke is advantageous, because it insures the total expulsion of air at each discharge—a result which is difficult to attain in dry air-pumps. Not only is a pump of this kind useful in manufactures 90 where air-pumps are used, but for philosophical or laboratory purposes. A very effective pump can be made at a low cost and much less than any piston air-pump. I make the lower end of the plunger conical, so as to reduce the 95 concussion when it strikes the liquid in its downstroke; and I prefer to use oil, as it effects the proper lubrication of the plunger. In pumping hot air and vapor, as is done in connection with a vacuum-pan, it might be desirable to employ water instead of oil and to constantly supply water to take the place of what is lost by evaporation. What I claim as my invention, and desire to secure by Letters Patent, is—
105
1. The combination, with a pump-chamber comprising a lower portion and an upper portion of larger diameter, of a plunger adapted to work in said chamber, and a discharge-valve surrounding the plunger and seating upon the chamber so as to control communication between the lower portion and the upper portion of larger diameter, substantially as herein described.
110
2. The combination, with a pump-chamber comprising a lower portion and an upper portion of larger diameter, of a plunger adapted to work in said chamber, and a discharge-valve surrounding the plunger, seating upon the chamber, and adapted to discharge the water 115 around its outer circumference, substantially as herein described.
120
3. The combination, with a pump-chamber and an annular discharge-valve seating thereon, of a plunger of wood adapted to work through said valve, and having a recess or depression in its top, substantially as and for the purpose described.
125
4. The combination, with a pump-chamber and an annular discharge-valve seating thereon, of a plunger working through and guided by the valve, and guides upon the chamber 130

fitting the exterior of the valve, substantially as herein described.

5. The combination, with a pump-chamber and plunger, of a loose ring fitting the exterior of the plunger, and having a seat near its circumference on the chamber, and capable of rising and falling so as to alternately close the chamber and form a discharge-valve, substantially as herein described.

10. 6. The combination of a pump-chamber comprising a lower portion and an upper portion of larger diameter, and having an open top, a plunger, and an annular discharge-valve surrounding the plunger, resting loosely on a seat on the chamber, and adapted to be removed through the open top of the chamber, substantially as herein described.

7. The combination of the chamber A, the plunger E, and the loose annular discharge-
20 valve D, seating on the chamber, and provided with a packing which fits the plunger, substantially as herein described.

8. The combination of the chamber A, the plunger E, and the loose annular discharge-valve D, seating on the chamber, and having 25 its inner face fitting the plunger and rounded or convex in a vertical direction, substantially as herein described.

9. The combination of the pump-chamber A, the loose annular discharge-valve D, and the 30 plunger E, having the taper k near its upper end, substantially as herein described.

10. The combination of the chamber A, the loose annular valve D, and the plunger E, having the taper k near its upper part and made 35 of reduced diameter above said taper, substantially as herein described.

HARVEY C. HALL.
